Atty's

UNITED STATES PATENT OFFICE.

GEORGE B. BERGEN, OF MILWAUKEE, WISCONSIN.

PENCIL.

Application filed November 27, 1920. Serial No. 426,836.

To all whom it may concern:

Be it known that I, GEORGE B. BERGEN, a citizen of the United States, and resident of Milwaukee, in the county of Milwaukee and State of Wisconsin, have invented certain new and useful Improvements in a Pencil, of which the following is a specification.

My invention relates to pencils and particularly to a novel, cheaply constructed pencil having many advantages not present in those heretofore suggested.

One of the principal objects of my invention is to provide a pencil which may be very cheaply constructed and in which the operating mechanism is of relatively extreme simplicity.

A further object is to provide actuating means located in the side of the pencil as distinguished from in the end. In the latter case much complication results all of which is avoided and ample opportunity is afforded for the mounting of a lead container and an eraser.

A further object is to so construct the pencil body as to provide means whereby the longitudinal axle bending may be formed without the necessity for longitudinal drilling. In pencils having wood bodies this is a source of great manufacturing difficulty and it is avoided in my construction by very simple means.

The invention will be better understood by reference to the accompanying drawings, wherein,

Fig. 1 is a side view of a pencil constructed in accordance with my invention;

Fig. 2 is an enlarged longitudinal sectional view showing the operating position of the parts;

Fig. 3 is a similar view showing the operating catch in position to advance the lead;

Fig. 4 is a plan view, and,

Figs. 5 and 6 are sectional views on the lines 5—5, 6—6, respectively, of Fig. 2.

In the drawings it will be seen that the pencil includes a body portion 10, which may advantageously be formed of wood, a metallic point 11, a lead container 12, and an eraser 13.

In preparing the body for the reception of the operating parts, I first form a longitudinal saw-cut 14, which is of a depth less than the radius of the body, and a second saw-cut 15, located at the axes of the body and of less width than the first cut.

The second saw-cut may well be of rectangu-

lar cross section and of a size substantially fitting a similarly shaped plunger or rack 16. The rack, as shown in Fig. 2, is provided with teeth or serrations 17 on its upper surface adapted to be engaged by a resilient pawl 18, secured at 18^a, to an arm 20. The arm is pivoted to a retaining member 19, of U-shape in cross section, the pin 18^a serving as a pivot for the arm. The arm is provided with depending side members 21, which fit snugly between the upstanding sides of the member 19. The body may be cut away at 22, to permit of engagement of the finger nail with the point 23 of the arm. It will be seen that the bottom portion of the U-shaped member underlies the plunger 16 and that when the plunger is in place the arm and attached pawl cannot be removed. The saw-cut 14 is filled by suitable strips 24, the outer surfaces of which conform to the outline of the pencil body. A space is left at the location of the actuating mechanism for the insertion and removal thereof.

In operation it will be seen that the pawl 18 engages the rack teeth on the top of the plunger 16 and provides a firm backing for the lead 25. When it is desired to advance the lead the arm is swung into the position shown in Fig. 3, whereupon the pawl slides upwardly on the rack. Upon pressing the arm the plunger is advanced correspondingly. If it is desired to retract the plunger or to disengage it from the actuating mechanism, the arm is swung upwardly to an extent sufficient to disengage the pawl from the rack. Upon removing the threaded tip 11, the plunger will drop of its own weight. Thereafter the actuating mechanism may be easily removed.

I claim:

1. In a pencil, the combination of a body having a longitudinal axial opening, a rack adapted to function as a plunger mounted in the opening, a U-shaped pawl-support 100 mounted in the side of the body, and a pawl pivoted in said support and adapted to engage the rack to effect the advance thereof.

2. In combination a pencil body having a longitudinal axial opening and a side opening communicating with the axial opening, a toothed plunger mounted in the axial opening, a U-shaped member mounted in the side opening, and a spring-actuated pawl mounted on said U-shaped member and 110 adapted to effect the advance of the plunger.

3. In combination a pencil body having an

axial opening and a side opening at a point substantially midway between the ends of the pencil, a rack mounted in the axial opening, a retaining member mounted in the side opening and having a portion underlying said rack, and a spring-actuated pawl mounted on said retaining member and adapted to effect the advance of the rack.

4. In combination a pencil body having an axial opening and a side opening at a point substantially midway between the ends of the pencil, a rack mounted in the axial opening, a retaining member mounted in the side opening and having a portion underlying said rack, and a spring-actuated pawl mounted on said retaining member and adapted to effect the advance of the rack, the retaining member and pawl being held in the side opening solely by the rack.

5. In a pencil, the combination of a body having an axial opening and a side opening communicating therewith, a rack mounted in the axial opening, a U-shaped member mounted in the side opening and adapted to underlie the rack, an arm pivoted to the U-shaped member and adapted to oscillate in an arc outside of the limits of the pencil body, and a spring-actuated finger movable with the arm and adapted to engage the rack to effect the advance thereof.

6. In a pencil, the combination with the body thereof, of means including a plunger for actuating a lead, said body being pro-

vided with a longitudinal saw-cut, and a second saw-cut of less width than the first mentioned cut, said second saw-cut being located in the axes of the body and substantially fitting the lead-actuating plunger.

7. A pencil having within its body a longitudinal bore, a toothed plunger slidably arranged within the bore, there being a recess within the body extending from the bore through to the outside thereof, a lever pivoted at one end within the recess and adapted normally to lie flush with the body, and tension means carried by the lever adjacent its pivoted end adapted with each swinging movement of the lever to engage the plunger to propel the same longitudinally through the pencil, substantially as described.

8. In combination with a pencil, a toothed plunger, means for guiding the plunger and a lead in advance thereof in longitudinal movements through the pencil, and means for propelling the plunger comprising a pivoted element having spring means adapted for resilient engagement with the plunger teeth, said means being moved lengthwise of the pencil with each oscillation of the element to thereby propel the plunger longitudinally of the pencil, substantially as described.

Signed at Milwaukee, Wisconsin, this 15th day of November, 1920.

GEORGE B. BERGEN.
